UNITED STATES PATENT OFFICE

2,228,602

OIL BURNER FURNACE

John L. Kolb, New Holland, Pa.

Application March 6, 1939, Serial No. 260,198

1 Claim. (Cl. 122—136)

This invention relates to improvements in boilers as described in the present specification and illustrated by the accompanying drawing that forms part of the same.

The invention consists essentially of the novel construction and arrangement of parts whereby water is heated between outer and inner jackets and the firebox supported by the inner jacket completely surrounded by water.

10 An object of the invention is to provide a furnace and boiler so combined as to cause the greatest possible transfer of heat from the combustion chamber and the flue gases to the water between the inner and outer jackets.

15 Another object of the invention is to provide a domestic hot water heater having a separate water system from that of the boiler while being housed within the boiler structure.

Another object of the invention is to provide 20 a cleanout box whereby soot, dirt, etc. may be readily cleaned from all parts of the flue passages and still another object of the invention is to provide a fuel burning furnace having a boiler built of easily renewable and assembled units of durable construction, of easy manufacture and reliable in use.

Other objects and advantages of the invention reside in certain novel features of construction, combination and arrangements of parts which will be hereinafter more fully described and pointed out in the appended claim, reference being had to the accompanying drawing forming part of this specification, and in which

Figure 1 is a view in longitudinal vertical section 35 of the boiler.

Figure 2 is a front view of the boiler, and;

Figure 3 is a rear view of the boiler.

Figure 4 shows a modified construction.

Referring to the drawing wherein for the sake of illustration is shown the preferred embodiment of the invention, the numeral 2 designates the outer jacket of the furnace supported from the floor by legs 3. Secured to jacket 2 are water inlet and outlet ports 4 and 5. 6 designates generally the main or front section of the inner jacket of the boiler which comprises a rectangular box of metal supported within the forward portion of the outer jacket in spaced relation to the walls thereof so as to be entirely surrounded by the water to be heated in the outer jacket. This inner jacket section 6 supports and completely surrounds the firebox 13. Disposed within the outer jacket 2 immediately in rear of the inner jacket section 6 is a hollow baffle or flue member 7 providing a flue passage 7a and spaced from

the section 6 to provide a water leg 7b. This hollow baffle wall or flue member 7 communicates at its bottom through an inlet passage 1c with the base of the section 6 in rear of the firebox. Enclosed in the outer jacket in rear of the hollow baffle wall 7 is an intermediate inverted U-shaped baffle wall or double baffle or flue member 8 providing flue passages 8a communicating at their lower ends with each other, and disposed in rear of the baffle member 8 is a rear wall baffle or flue member 9 forming a flue passage 9a communicating at the bottom of said member with an outlet pipe 9c extending outwardly through the rear wall of the jacket 2. The hollow baffle walls are connected at their upper ends with each other 15 by pipes 10 and 11. The several baffle members extend almost completely across the jacket 2 and the construction and arrangement of the baffle members 8 and 9 is such as to form water legs 20 8b, 8c, 8d and 9b which are parallel with each other and with the water leg 7b. The hollow baffle walls 8 and 9, instead of being separately formed, may be cast integrally with the main jacket 6 and with each other in which case the connecting pipes 10 and 11 would not be used as the tortuous 25 flue passage would be continuous. The main or front section of the inner jacket 6 is provided with an opening 12 at its front, from its base to a height that will just clear the top of the firebox 13, which is adapted to be slid in and out through 30 a doorway formed by said opening and a similar rectangular opening 14 in the outer jacket 2, the space between the walls of the jackets around the marginal edges of the doorway being suitably closed. A removable heat insulating block 15 is 35 provided to normally seat within this doorway in front of the firebox. The outer portion of the doorway formed by the rectangular opening 14 in the outer jacket 2 is closed by a plate 16 detachably secured to the front of the jacket 2 40 and having an opening 17 therein registering with openings 17' and 18 in the block 15 and front of the firebox 13 through which a combustion unit such as an oil burner may be placed for cooperation with the firebox 13. The block 15 is suitably 45 secured either to the plate 16 or to the front of the firebox so as to be withdrawn therewith when it is desired to remove the firebox. Forming part of inner jacket 6 is a pipe 20 which extends through the front of the inner jacket 2 and is 50 normally closed by a heat insulated inspection door 21. A standard flame detector 22 forms another extension of jacket 6 and projects through an opening in the outer jacket 2. A clean-out box 23 of rectangular formation extends through 55

one side of the outer jacket 2 near its base and enters one wall of the baffle or flue member 7 and the intermediate baffle or flue member 8 of the boiler, said box being closed by a clean-out plate 24 secured to outer jacket 2. A domestic hot water heater 25 consisting of U-shaped pipes is extended through the rear of jacket 2 and lies in a plane parallel to the top of the boiler and is secured to the outer jacket by means of a collar 26.

In operation the space between the inner and outer jackets and the water legs will be filled with water through inlet pipe 4. The heat of the combustion chamber 13 will be transferred to the water surrounding the inner jacket 6 and the products of combustion will pass through the flue passages of the hollow baffle walls 7, 8 and 9 to a flue connection secured to the pipe 9a at the base of the baffle wall section 9. By this peculiar construction of the furnace it is readily seen that the greatest possible amount of heat is absorbed by the water within my furnace. The construction of the boiler is made of easily renewable parts which upon failure may be replaced cheaply and by unskilled labor. The clean-out plate 24 may be removed so that the soot and ashes of the products of combustion may be easily removed from the main and intermediate inner jackets 6 and 8. The domestic hot water heater 25 is for the purpose of heating water for household use, and while nothing novel is claimed for its construction this peculiar combination and its position within the boiler makes for a very efficient

and satisfactory means of conveying heat to the water within said heater. The front of the boiler is provided with the usual aquastate 27 and thermometer 28 by which the temperature may be set and observed.

What is claimed as new is:

A boiler for a heating system comprising an outer jacket and an inner jacket arranged to form therebetween a chamber for fluid to be heated, said inner jacket being arranged within the front portion of said outer jacket, the front wall portions of said jackets having registering apertures therein, a firebox adapted to be supported within said inner jacket, said firebox being insertable and removable through said apertures, a removable closure adapted to seal said aperture in said outer jacket, said closure including a removable heat insulating member adapted to seal the space around said firebox and between the walls of said jackets in which said apertures are formed, and a plurality of spaced interconnected hollow baffle walls disposed within the rear portion of the outer jacket between the inner jacket and the rear wall of the outer jacket, and extending transversely within the remaining space within the outer jacket, said baffle walls being arranged to provide a tortuous flue for the passage of the combustion gases, the baffle wall adjacent said inner jacket being in communication at its base with the inner jacket in the rear of, and below the upper edge of said firebox.

JOHN L. KOLB.
